UNITED STATES PATENT OFFICE

KARL BAHRMANN, OF DRESDEN, GERMANY, ASSIGNOR TO KOCH & STERZEL AKTIEN-
GESELLSCHAFT, OF DRESDEN, GERMANY, A COMPANY OF GERMANY

HIGH TENSION TRANSFORMER

Application filed July 14, 1930, Serial No. 467,900, and in Germany July 27, 1928.

My invention relates to transformers, and particularly to high potential transformers of the type in which the high potential winding consists of disc-windings arranged on a 5 unitary spool. It has been found that, with a layer-wise winding arranged in a unitary insulating spool box and so connected that the potential increases from the outermost layer towards the core, the commencement of 10 the innermost winding being guided through the flange of the spool box, oil insulation for the windings of the transformer is not essential.

The object of this invention is to provide a 15 transformer having disc-shaped windings which has the advantage that oil insulation for said windings is unnecessary and, to achieve this result, the spool body surrounding the iron core is formed of two insulating 20 concentric annular tubes, said tubes being bridged at one end to form an annular recess so that the whole constitutes an insulating body of substantially U-shape in cross-section which is made up of two concentric tubes 25 each having one edge joined to the adjacent edge of the other or which may have their edges at one end joined. The windings are inserted into the recess through the open end thereof, the winding end adjacent the bridged 30 or closed end being led out through an insulator formed integrally with the spool body.

As in this type of transformer the potential increases in the direction of the axis of the windings, the annular recess within which 35 said windings are housed may be tapered inwardly towards the winding end carrying the higher potential, the several disc windings gradually decreasing in size in the same direction. This arrangement provides for a reduction 40 of the short circuit potential and also for the building of a very compact transformer.

A further feature of the invention resides in the fact that two unitary spool bodies of the type disclosed may be telescoped one 45 within the other whereby the lead-out insulators are disposed on opposite sides of the transformer, whilst both poles may be insulated from earth.

In the drawings,
50 Figures 1 and 2 show vertical sectional

views of the transformer according to the invention in planes at 90° to each other,

Figure 3 is a vertical section of a modified construction of the transformer,

Figure 4 shows in section a bi-polar transformer having two spool bodies telescoped one within the other, 55

Figures 5 and 6 show in elevation and plan respectively a three phase transformer according to the invention, 60

Figure 7 shows in elevation an upright bi-polar transformer and

Figure 8 shows the method of suspending a 65 transformer of the pillar type having an insulated iron core.

Around the core 11 there is disposed the secondary winding 12 surrounded by a unitary insulating body consisting of a pair of concentric annular tubes 13, 14 bridged or closed at one end as at 15 and a lead-out insulator 70 16. In the recess between the two tubes 13, 14 are located the individual disc windings 17 and between each of said windings there is arranged an insulating disc 18. These discs are formed as annular ribs on an insulating tube 75 19 surrounding the inner tube 13 of the spool so that the high potential winding may be assembled outside the spool body and then bodily inserted into the recess. It will be seen that by reason of the present arrangement of parts there is provided an insulating body of inverted U-shaped cross-section which is made up of two concentric tubes each having one edge joined to the adjacent edge 80 of the other. 85

The commencement 20 of the high potential winding is placed upon the earthed iron core 11 so as to be electrically connected thereto, whilst the other end of the winding is connected to one end of a slit metal ring 90 21 fitting within the recess formed between the tubes 13, 14 and being located adjacent the closed end thereof. The other end 22 of the ring may be either connected to the lead-out wire or said lead-out may be formed by 95 an upwardly directed extension of said ring. The ring thus forms the first or input turn of the high potential winding. Extending from the glow ridge 23 on the lead-out insulator over the outer and inner surfaces of 100

the spool body and over the bridging or closing portion 15 is a conductive coating 24 obtained, for example, by sprayed metal or graphite, such as is shown in broken lines 5 in Figure 2. The open or under side of the insulating body is covered by means of a plate 25 secured to the core.

The insulator 16 may, if desired, be arranged to project horizontally of the transformer 10 whereby the structural height is substantially reduced.

In the modification shown in Figure 3, the general arrangement of which is similar to that above described, the two tubes 13, 14 15 decrease in thickness towards the open end thereof which results in the formation of a tapered recess for the high potential winding. This tapering of the recess is so arranged that the thicker portions of the tubes 20 lie adjacent those parts of the winding carrying the higher potential. It is not essential, however, to decrease the size of the recess in order to provide an increasing thickness of insulating wall towards the winding end carrying the high potential. Thus the outer sides of the members forming this recess tapered outwardly towards the closed end. It is also possible, by means of the closing or bridging part 15 and a flange 26 attached 25 thereto to secure the transformer to the wall or ceiling of a switch-house.

In Figure 4 a high potential transformer is shown in which neither of the two connecting poles reverse. In this construction two 35 unitary insulating bodies 27, 28 are telescoped, one into the other, in opposite directions so that the lead-out insulators for the two poles lie on opposite sides of the transformer.

40 In Figures 5 and 6 there is shown a three phase transformer comprising three units of the type shown in Figures 1 and 2. These separate units are mounted on a triple shouldered iron core 30 whereby the complete 45 transformer can be made more compact than is usual. In order, however, that the insulators 16 may be sufficiently spaced they are arranged in somewhat staggered formation, the distances a, b being thereby increased.

50 Figure 7 shows the arrangement of two transformer units of the form shown in Figures 1 and 2 mounted on the arms of a two-shouldered iron core. The core is mounted on insulators and the centre of the high potential winding is connected therewith, 55 through the open ends of each spool body to obtain a double potential at the lead-out point.

As shown in Figure 8 the two units of a 60 bipolar transformer of the type shown in Figure 7 can be constructed in a manner known per se to form a suspended column, the high potential windings being connected in cascade.

65 Thus there is produced, according to the in-

vention, a high potential transformer in which the insulation of the high potential winding is obtained without the use of sealing compounds or insulating liquid. The potential drop due to the disc-shaped high potential winding and the arrangement of the annular concentric insulating tubes enclosing said winding ensure the prevention of short circuiting voltages between non-adjacent disc windings.

What I claim and desire to secure by Letters Patent of the United States is:—

1. In a high potential transformer having an insulated body provided with spaced outer and inner annular walls connected at one end and open at the other, a secondary winding positioned within the inner wall and a disc-shaped high potential winding mounted within the opening between the inner and outer walls.

2. In a high potential transformer having an insulated body provided with spaced outer and inner tapered annular walls connected at one end and open at the other, a secondary winding positioned within the inner wall, and a disc-shaped high potential winding within the opening between the inner and outer walls.

3. In a high potential transformer having an insulated body provided with spaced outer and inner tapered annular walls connected at one end and open at the other, a secondary winding positioned within the inner wall, and a disc-shaped high potential winding within the opening between the inner and outer walls, the thickness of said walls increasing towards the closed end thereof.

4. In a high potential transformer having an insulated body provided with spaced outer and inner tapered annular walls connected at one end and open at the other, a secondary winding positioned within the inner wall, and a disc-shaped high potential winding within the opening between the inner and outer walls, the thickness of the walls increasing towards the winding end carrying the high potential.

5. In a high potential transformer having an insulated body provided with spaced outer and inner annular walls connected at one end and open at the other, a secondary winding positioned within the inner wall, a disc-shaped high potential winding mounted within the opening between the inner and outer walls, and a split ring forming a turn of the high potential winding, said ring being located adjacent the closed end of the body.

6. In a high potential transformer having an insulated body provided with spaced outer and inner concentric walls connected at one end and open at the other, a secondary winding positioned within the inner wall, an iron core extending axially within said secondary winding, a disc-shaped high potential winding mounted within the opening between

the inner and outer walls and connected to said iron core, and a cover plate for the opened end of the transformer.

7. In a high potential transformer having an insulated body provided with spaced outer and inner concentric walls connected at one end and open at the other, a secondary winding positioned within the inner wall, an iron core extending axially within said secondary winding and connected to one end of the high potential winding, a cover plate for the opened end of the body, means securing the cover plate to the iron core, the closed end of the body having a supporting flange extending therefrom.

8. In a high potential transformer having an insulated body provided with spaced outer and inner annular walls connected at one end and open at the other, a secondary winding positioned within the inner wall and a high potential winding mounted within the opening between the inner and outer walls.
